UNITED STATES PATENT OFFICE.

EUGENE B. HIGGINS, OF EAST ORANGE, NEW JERSEY.

DESIGN FOR A TOOL HANDLE AND RECEPTACLE.

SPECIFICATION forming part of Design No. 33,589, dated November 20, 1900.

Application filed June 5, 1900. Serial No. 19,178. Term of patent 14 years.

To all whom it may concern:

Be it known that I, EUGENE B. HIGGINS, a citizen of the United States, residing at East Orange, Essex county, in the State of New Jersey, have invented and produced a new and original Design for a Tool Handle and Receptacle, of which the following is a specification, reference being had to the accompanying drawings, forming part thereof, in which—

Figure 1 is a side view of a tool handle and receptacle embodying my design. Fig. 2 is a top or plan view.

The leading feature of my design consists of a handle and receptacle having one end rounded and of a bulbous formation, the opposite end having a cylinder-shaped offset portion of less diameter than the main portion of the handle and extending therewithin, an annular recess being formed extending around the periphery of said offset portion, said offset portion having a series of concen-

trically-arranged pockets or recesses on its end face, the portion of the handle intermediate its ends being curved to symmetrically connect the ends. 25

In the drawings, A designates the handle and receptacle; B, the handle proper; C, the rounded end; D, the intermediate portion of the handle; E, the end opposite B; G, the offset portion extending within the handle; F, the recess extending around the offset portion; H, the concentrically-arranged pockets or recesses, and I a central opening. 30

What I claim is—

The design for a tool handle and receptacle, substantially as shown and described.

Signed at the city of New York, in the county and State of New York, this 4th day of June, 1900.

EUGENE B. HIGGINS.
